UNITED STATES PATENT OFFICE.

JOHN E. SEDERHOLM, OF ST. PAUL, MINNESOTA, ASSIGNOR, BY DIRECT AND MESNE ASSIGNMENTS, OF ONE-HALF TO ENOCH N. HOLSTROM, OF ST. PAUL, MINNESOTA.

TROLLEY-WHEEL.

1,355,575.

Specification of Letters Patent. Patented Oct. 12, 1920.

Application filed October 6, 1919. Serial No. 328,889.

To all whom it may concern:

Be it known that I, JOHN E. SEDERHOLM, a citizen of the United States, residing at St. Paul, in the county of Ramsey and State 5 of Minnesota, have invented certain new and useful Improvements in Trolley-Wheels; and I do declare the following to be a full, clear, and exact description of the invention, such as will enable others 10 skilled in the art to which it appertains to make and use the same.

This invention relates to improvements in trolley wheels and it has more particular reference to the mounting therefor, it being especially designed for use on cranes, 15 although it is not to be restricted to such use.

Trolley wheels now in use on cranes are ineffective in transmitting current from 20 the trolley wire to the motors because of poor contact between the bearing pin and wheel. By reason of this fact alternating currents oftentimes become unbalanced in the different phases, thus causing them in many 25 cases to run on single phase, and in this way burn the motor out. On direct current circuits bad contact means inrushes, and heavy currents, thereby damaging the motor. The present trolley wheels also 30 wear unevenly against the bearing pin, which thus causes them to cant and cause poor contact. This means that the wheel oftentimes jumps the trolley wire, and sometimes wears the trolley wire through.

35 It is therefore the object of this invention to provide a trolley wheel and mounting therefor which is of such construction that it will overcome, to a great extent, the above mentioned defects.

40 Another object of the invention is to provide a device of the character stated which is simple in construction, strong, durable, effective in use, and comparatively inexpensive to manufacture.

45 Other objects and advantages of the invention will become apparent during the course of the following description.

In the accompanying drawings forming a part of this specification and in which like 50 numerals are employed to designate like parts throughout the same,

Figure 1 is a central longitudinal sectional view, partly in elevation, of a trolley constructed in accordance with my invention.

Fig. 2 is a section on the plane of the line 2—2 of Fig. 1.

Fig. 3 is a section on the plane of the line 3—3 of Fig. 1.

Fig. 4 is a detail view of the contact 60 brush.

Fig. 5 is a transverse view on the plane of the line 5—5 of Fig. 4.

In the drawings, wherein for the purpose of illustration is shown a preferred 65 embodiment of my invention the numeral 1 designates a bearing pin upon which the trolley 2 is mounted for rotation. This bearing pin is provided with a longitudinal bore 3 adjacent one of its ends, and as shown 70 its length is equal to approximately one half of the entire length of the pin 1. Longitudinally slidable in the bore 3 is a contact brush 4 which is pressed outward by the action of the coiled spring 5, also fitted in 75 said bore. In order to prevent annealing of the spring 5 by the current that might otherwise pass through it, I interpose an insulating member 6 between the brush and spring. This brush 4 is preferably in the 80 form of a hollow split sleeve and is provided at one of its ends with a solid portion or head 7, and this head normally projects beyond the open end of the bore 3, or, in other words, beyond the end of the pin 1. 85 The opposite end of the brush 4 is of a slightly greater diameter at 8 than the already mentioned end and this serves to retain it in the bore of the bearing pin 1, as is obvious.

90 The trolley wheel 2 is provided with an opening 9 which extends transversely therethrough. One end of this opening is closed by a removable cap or closure 10 which is provided with a socket 11 to receive the 95 head 8 of the brush therein. The other end of the opening 9 is closed by a removable plate 12 which is held in a closed position by a thick circular wire member 13 which fits into an annular groove in the wheel 2 100 as shown.

A series of ball bearings 14 are interposed between the cap 10 and plate 12 and serve to reduce friction between the parts. These ball bearings are held in a ball retainer 15 105 and the whole device is positioned between the longitudinally grooved bushings or collars 16. In order to prevent current from passing through the ball bearings and causing them to deteriorate, I employ an 110

other bushing or collar 17 of insulating material which is fixed on the pin 1 and also serves to retain the wheel 2 on the pin 1, as is obvious.

5. The electrical conductor shank (not shown) which furnishes the motors of the crane with current is connected to the pin 1 between the flange 18 and nut 19 and is thus prevented from bearing against the wheel 10 and loosening it from the pin 1.

In use the current passes from the trolley wire through the wheel 2, through cap 10, through the brush 4 which is pressed into contact with cap 10, and then through the 15 pin 1.

When it is desired to insert a new brush it is only necessary to remove cap 10 which is employed for that purpose. On the other hand when it is desired to replace the ball 20 bearings 14 or bushing 16, it will be necessary only to contract the wire retainer 13 and remove it from the groove in which it is seated, whereby the plate 12 may be readily removed.

25. Although there will be considerable wear between the head 8 of the brush and the socket 11, it will be seen that the spring 5 will always keep them in tight contact.

A device of the above described construction is effective in use in that any one of or all of the parts may be easily and readily renewed, thereby saving the expense of buying a whole new device. It is adjustable, that is different sizes of conductor shank 30 35 may be effectively connected to the bearing pin 1 because of its construction. Friction between the parts is greatly reduced thus preventing excessive wear of the parts.

It is to be understood that the form of my 40 invention herein shown and described is to be taken as a preferred form of the same, and that various changes in the shape, size and arrangement of parts may be resorted to without departing from the spirit of the 45 invention or the scope of the subjoined claims.

Having thus described my invention and best way known to me of making and using the same, I claim:—

50. 1. A device of the character set forth comprising a bearing pin having a longitudi-

dinal bore therein, a spring pressed contact brush longitudinally slidable in said bore, and a trolley wheel mounted for rotation on said pin, said brush contacting with a part 55 of said wheel to permit an electrical current to pass therethrough, substantially as set forth.

2. A device of the character set forth comprising a bearing pin having a longitudinal bore adjacent one of its ends, a coiled spring in said bore, a slidable contact brush in said bore, an insulating member interposed between said coiled spring and brush, a trolley wheel mounted for rotation on said 65 bearing pin, said brush contacting with a part of said wheel to permit an electrical current to pass through said wheel, brush and pin, substantially as set forth.

3. A device of the character set forth comprising a bearing pin having a longitudinal bore adjacent one of its ends, a coiled spring, insulating member and a contact brush longitudinally movable in said bore, said brush being in the form of a split sleeve having a 70 contact head thereon, said head normally projecting beyond one end of said bearing pin, and a trolley wheel mounted for rotation on said pin, said head of the brush contacting a part of said wheel to permit an 75 electrical current to pass through said wheel, brush and bearing pin, as set forth.

4. A device of the character set forth comprising a bearing pin having a longitudinal bore therein adjacent one of its ends, a longitudinally slidable spring pressed contact brush in said bore, said brush normally projecting beyond one end of said bearing pin, a trolley wheel mounted for rotation on said 85 bearing pin, said wheel having an enlarged 90 opening extending transversely therethrough, a removable cap closing one end of said opening, said cap having a socket therein adapted to receive the projecting end of said brush, a removable plate closing the opposite end of said opening, means to retain 95 said plate in position, and anti-friction means disposed between said cap and plate, substantially as set forth.

In testimony whereof I have hereunto set 100 my hand.

JOHN E. SEDERHOLM.
